UNITED STATES PATENT OFFICE.

TERRICE G. BRADY AND CELIA NELKIN, OF NEW YORK, N. Y.

FABRIC GRIP.

Application filed September 1, 1926. Serial No. 132,988

This invention relates to the textile fabric supports in which the ends of one or more thicknesses of cloth folded lengthwise may be securely engaged or disengaged at will, and more particularly to sanitary serviettes used as catamenial absorbers.

Such devices in order to fulfill the requirements satisfactorily must exert a powerful grip or clamping effect upon the fabric, be easily applied or removed with facility, and avoid the use of buttons, pins, hooks and the like types of common fastenings.

In addition to affording positive security to the article supported the present device has the advantage of tending to spread and flatten the folded fabric, preventing it from swaying, relative to the support, whereby it may become loosened accidentally, the spreading effect operating very materially to reduce excessive bulkiness, rendering the connection unusually compact.

Other features of the invention are in its light weight, simplicity and inexpensive construction, all of which will appear in the following description, taken in connection with the accompanying drawing, forming a material part of this disclosure, and in which:—

Figure 1 is a general front elevation of an embodiment of the invention showing one of its applications.

Fig. 2 is an enlarged front view of the same as detached.

Fig. 3 is a side view of the same indicating the manner of inserting a fabric between and over the loops.

Fig. 4 is a front elevational view of a support having a modified holding device and engaged with a wider flexible element.

The subject matter of the invention is best seen in detail in Figs. 2 and 3 in which two distinct loop elements 10 and 11, respectively front and rear appear, each being composed of a single strand of wire made of non-tarnishable material, or plated for that purpose.

The rear loop 11 consists of a straight cross bar 12 of any suitable length having curved ends blending into parallel side members 13, having in their length outstanding eyes 14, formed by single coils, the continuing portions being offset outwardly and bent at right angles towards each other to constitute sections of an upper bar 15.

The inreaching ends of the sections may

be coiled interengagingly as at 16, whereby they are rigidly united, or the ends may merely abut as indicated in Fig. 1, or again, they may be connected by twisting, as at 17 in Fig. 4, the ends of the twisted strands reaching thereabove to form a looped eye 18 to engage over a fixed support 19, as a nail or pin.

The front loop 10 is composed of a pair of substantially closed hooks 20, freely engaged in the eyes 14, which are so disposed as to prevent the hooks from turning outward more than ninety degrees therein, these hooks being formed on the ends of side members 21 extending normally in overlying relation to the lower portions of the rear loop members 13.

The lower portions of the side members 21 are bent slightly outward to merge into corner bows 22, the inner elements of which reach past the bar 12, to at least a distance equal to the diameter of the wire, and then extended in alinement towards each other to constitute a bar 23.

The inner ends of the bar sections 23 are integrally connected by a downwardly extending lobe 24, reaching considerably below bar 12, as best seen in Fig. 2, these bows and lobe constituting outstanding undulations which positively prevent the front loop from being drawn through the rear loop, irrespective of looseness, wear or resilience of the parts.

In Fig. 1 is shown a waist band 25 having elastic insert 26 at the sides and provided with any preferred type of fastening means, not shown; at the front and rear are pendant elastic tapes 27, either doubled or hemmed at their lower edges, to receive the loop bars 15 and securely support the same.

A serviette 28, after having been properly folded, has its ends passed over both loops 10 and 11, turned to engage around the front loop 10, as at 29, and then have its extreme end 30, tucked in between the bar 12 and the overlying portion of the serviette, as best seen in Fig. 3.

Due to the excessive lengths of the lobe 24, the material of the serviette is not only centered but caused to spread edgewise when adjusting the fabric and upon drawing the material rearwardly, the front loop is caused to forcibly clamp the same tightly against the rear loop and thereafter, due to the undulations, retain the serviette positively and securely in adjusted position.

As there are no sharp corners or edges on the device whatever, the material cannot be cut or injured, and it will be seen that when it is desired to release the same, the covered lobe 24 acts conveniently as a catch for withdrawing the front loop by swinging it outwardly and thus liberate the fabric.

In the modification shown in Fig. 4, a towel is shown supported by a nail or a pin 10 19, fixed in a wall or other support.

While the foregoing is descriptive of the preferred embodiment of the invention, it is to be understood that minor structural changes may be made and also the proportion 15 of parts within the scope and spirit of the claims.

Having thus described our invention, what we claim as new and seek to secure by Letters Patent, is:—

1. A device of the class described comprising a unitary substantially rectangular wire rear loop having a pair of eyes formed in the upper part of its side members, and a straight batten bar member connecting the 20 sides, a second loop having hooked ends engaged in said eyes, the sides of the second loop registering with the sides of the first member, and an undulating bar connecting the sides of the second member, the undulations 25 of said bar extending beyond the sides and bottom of the first loop.

2. A device of the class described comprising a unitary substantially rectangular wire rear loop having a pair of eyes formed in the upper part of its side members, a second wire loop having hook ends engaging said eyes, said eyes being so positioned as to limit the turning movement of said hooks, the sides of the second loop being in register with the sides of the first loop, an undulating bar member connecting the sides of the second loop and crossing the connecting member of the first loop, and a central down reaching lobe on said bar to act as a finger grip and to positively grip the fabric. 35 40 45

3. A device of the class described comprising a unitary wire loop having angularly disposed outstanding eyes in its side members and straight connections between the side members, a second loop having 50 hooks connecting in said eyes whereby it may be swung partially open, an undulating connection between the sides of the second loop whereby the undulations cross the side and bottom members of the first loop, and 55 an extending lobe intermediate the length of said connection.

Signed at New York, county of New York and State of New York, this 16 day of August, 1926.

TERRICE G. BRADY.
CELIA NELKIN.
